UNITED STATES PATENT OFFICE.

JOSEPH MUELLER, OF ST. LOUIS, MISSOURI.

SELF-OILING DIE-STOCK.

No. 895,881.

Specification of Letters Patent. Patented Aug. 11, 1908.

Application filed October 22, 1907. Serial No. 398,647.

To all whom it may concern:

Be it known that I, JOSEPH MUELLER, a citizen of the United States, residing at St. Louis, in the county of St. Louis, City and State of Missouri, have invented new and useful Improvements in Self-Oiling Die-Stocks, of which the following is a specification.

This invention relates to die stocks, and more particularly to devices for oiling the work cut by the dies.

The invention has for one of its objects to improve and simplify the construction and operation of devices of this character so as to be comparatively easy and inexpensive to manufacture, reliable in use, and convenient to manipulate.

A further object of the invention is the provision of a die stock in which the handle or handles constitute reservoirs for lubricant.

Another object is the employment of an oil feeding device between the handle and body of the stock, which device is controlled by a rotary movement of the handle for opening the supply of oil and cutting it off.

The invention has as a further object to provide a die stock having a lubricant feeding device controlled by a handle of the stock, the handle being automatically maintained in a position to prevent the flow of lubricant.

With these objects in view and others, as will appear as the description proceeds, the invention comprises the various novel features of construction and arrangement of parts which will be more fully described hereinafter and set forth with particularity in the claims appended hereto.

In the accompanying drawing, which illustrates one of the embodiments of the invention, Figure 1 is a central longitudinal section of the die stock with parts in elevation and equipped with the self-oiling attachment. Fig. 2 is a central longitudinal section of one of the handles of the stock showing the lubricant feeding device. Figs. 3 and 4 are transverse sections on lines 3—3, Fig. 4, showing the position of the oiling device in feeding position and closed position, respectively.

Similar reference characters are employed to designate corresponding parts throughout the several views.

In the present instance, I have elected to illustrate the invention in connection with a stock commonly known in the trade as the duplex adjustable die stock, but it is to be

understood that the invention is not necessarily limited to a stock of this type.

Referring to the drawing, A designates the body of the stock which is provided with tubular extensions or arms 1, on which are swiveled the handles B of the stock. The handles B are tubular and extend into the arms 1 to which they are attached by means of a nut 2 threaded on each arm 1 and engaging an annular flange 3 on the handle. The outer extremities of the handles have filling openings 4 that are normally closed by screw plugs 5, whereby the lubricant is prevented from flowing out as the die is turned. Each arm 1 has an internal annular shoulder or seat 6, on which is seated a plug 7 which is provided with a short piece of tube 8 that passes through a radial opening 9 in the sleeve 10 of the stock and terminates adjacent the dies 11 so as to discharge lubricant on the latter and work cut thereby. The member 7 is frictionally held in place in the arm 1, and extending outwardly is a central air inlet tube 12, Fig. 2, which projects into the handle B, and connected with the inner end of the handle is a valve C which is adapted to control the flow of lubricant from the handle. This valve is in the form of a disk having a central aperture 13 to receive the air inlet tube 12, and it is removably connected with the handle by a screw thread 14. The valve has a port or passage 15 extending entirely through the same and adapted to be brought into register with the oil feeding tube 8, and the valve has another angular port 16 that registers with a port 17 in the plug 7 when the port 15 registers with the tube 8, and at the same time also registers with an opening 18 in the air inlet tube 12 so that air can enter the handle as lubricant is fed therefrom. Normally, the handle is in such a position that the flow of lubricant and entrance of air are cut off, and the handle is held in this position by a helical torsion spring 19 that has its outer end engaged in a slot 20 in the air inlet tube and its inner end engaged in a recess 21 in the valve, the tension of the spring acting to hold the parts in the position shown in Fig. 4. For limiting the angular movement of the handle, the valve has a peripheral flange 22 which extends three quarter way around the same so as to leave a quadrant recess 23 whose end walls 24 are adapted to engage with a pin 25 extending outwardly from the relatively

fixed plug or member 7.

In practice, the screw plugs 5 of the handles are taken out and the handles filled one after the other with lubricant. Since the valve-closing springs 19 hold the handles so that the ports 15 and 16 do not register respectively with the tube 8 and port 17, as shown in Fig. 4, no lubricant will feed from the handles. When the stock is applied to a piece of work to be threaded, the dies and work can be lubricated by merely turning one or both handles so that the ports will register, as shown in Fig. 3, thereby permitting oil to pass through the ports 15 and tubes 8, while air enters through the ports 17, 16 and 18, and tubes 12. As soon as the handles are released, the springs 19 will return the handles to normal position and thereby cut off the flow of oil and close communication between the atmosphere and handles. It will thus be seen that the lubricating devices are easy and convenient to operate and dispense with the need of the usual oil can, thereby saving time and permitting the cutting operation to be continuous without stopping to apply lubricant.

From the foregoing description, taken in connection with the accompanying drawing, the advantages of the construction and of the method of operation will be readily apparent to those skilled in the art to which the invention appertains, and while I have described the principle of operation of the invention, together with the apparatus which I now consider to be the best embodiment thereof, I desire to have it understood that the apparatus shown is merely illustrative and that such changes may be made when desired as are within the scope of the claims.

Having thus described the invention, what I claim is:

1. The combination of a die stock having a tubular arm, a hollow handle fitted therein for rotary movement, said handle constituting a reservoir for lubricant, a duct leading from the handle to the socket of the die for lubricating the work, and a valve in the arm arranged to be opened and closed by the rotary movement of the handle.

2. The combination of a die stock provided with a socket having a hollow arm, a ported plug in the arm, a feed tube in the stock and extending from the port of the plug to the said socket, a rotatable handle on the arm and constituting a reservoir for lubricant, a valve secured to the arm and arranged to be moved to open or closed position by the latter for permitting lubricant to feed to the said tube.

3. The combination of a die stock provided with a tubular arm, a handle mounted thereon for rotary movement and constituting a reservoir for lubricant, a fixed plug in the arm and having tubes extending one into the handle and the other into the die stock, and a valve secured to the handle arranged to per-

mit the air to enter the handle through one tube and lubricant to feed from the handle to the other tube, and a spring operating on the handle to hold the valve in closed position.

4. The combination of a die stock comprising a body, and a handle rotatably mounted thereon and forming a lubricant-containing reservoir, with a device arranged between the stock and handle dependent upon the movement of the latter for opening and cutting off the supply of lubricant.

5. The combination of a die stock comprising a body, a hollow handle rotatably mounted thereon and serving as a reservoir for lubricant, means for supplying lubricant from the handle to the dies of the stock, and a valve device secured to the inner end of the handle and arranged and constructed to be opened and closed by the movement of the latter for controlling the supply of lubricant.

6. The combination of a die stock comprising a die carrying body, a hollow handle mounted thereon to turn and forming a lubricant-containing reservoir, means arranged between the stock and handle for supplying lubricant from the latter to the dies, means for admitting air to the handle, and a valve controlling both means and movable with the handle.

7. The combination of a die stock comprising a die carrying body, a hollow handle mounted thereon to turn and forming a lubricant-containing reservoir, means between the stock and handle for supplying lubricant from the latter to the dies, means for admitting air to the handle, a valve controlling both means and movable with the handle, and a spring operating on the handle for holding the valve in closed position.

8. The combination of a die stock consisting of a body having a tubular arm, a hollow handle removably and rotatably mounted in the arm and forming a lubricant-containing reservoir, a fixed member in the arm, a tube connected with the member and leading into the body of the stock for supplying lubricant to the dies, an air inlet tube on the member extending into the handle, a valve removably connected with the inner end of the handle and provided with ports adapted to register with the said tubes for permitting air to enter the handle through one tube and lubricant to flow to the dies through the other tube, means for limiting the rotary movement of the handle, and a spring arranged to automatically return the handle to normal position for cutting off the supply of lubricant to the dies.

In testimony whereof I affix my signature in presence of two witnesses.

JOSEPH MUELLER.
